DISTRIBUTION UNIT FOR THREE-WIRE SYSTEMS

Richard P. Ballou, Hartford, Conn., assignor to
 Federal Electric Products Company, Newark,
 N. J., a corporation

Application April 7, 1950, Serial No. 154,559

10 Claims. (Cl. 175—298)

1

This invention relates to fuse blocks, and more especially to fused switch blocks, for three-wire distribution systems.

In the usual fuse blocks or fused switch blocks for a three-wire distribution system, it has heretofore been the practice to provide a neutral terminal block or connector device structurally separate from the fuse block itself. This is undesirable because it complicates and renders difficult the correct wiring of the several branch circuits to the companion fuse and neutral terminals, respectively, and increases the possibility of erroneously wiring the branch circuits to the companion fuse terminals.

It is, therefore, one of the objects of the present invention to provide, especially for three-wire distribution, a fuse block for a plurality of branch circuit connections each of which is provided with a companion fuse receptacle having its terminals so arranged in relation thereto on the block that they are readily apparent as being the companion live and neutral-wire terminals of the companion fuse receptacle, thereby obviating the need for a separate neutral-wire terminal block, or connector, and decreasing the possibility of errors in wiring.

Another object of the invention is to provide a compact integral distribution unit for main and branch circuit switches and fuses or circuit interrupters.

It is another object of the present invention to provide a fuse block of this type having lead-in terminals arranged to facilitate their connection with the line wires, respectively, including the neutral wire thereof.

It is another object of the present invention to provide a fused switch block of this type in which the lead-in terminals for the line wires are arranged at one end of the block near a centrally located main switch or circuit interrupter thereon, and the companion terminals for the branch circuit connections are arranged in equal rows on the opposite sides, respectively, of the block and properly connected with the disconnect side of the main switch and with the lead-in terminal for the neutral line wire by different bus bars in the block.

It is another object of the present invention to provide a fused switch block of this type having a main pull-out type switch for opening and closing all branch circuits, as well as one or more auxiliary pull-out type switches for opening and closing one or more of these branch circuits independently of the other branch circuits.

The above and other objects, features and ad-

2

vantages of the present invention will be more fully understood from the following description considered in connection with the accompanying illustrative drawings.

5 In the drawings:

Fig. 1 is a front elevational view of an enclosed fuse block embodying the present invention;

Fig. 2 is a side elevational view of the panel box in which the instant fuse block is enclosed;

Fig. 3 is a front elevational view of the enclosed fuse block with the cover of the panel box removed;

Fig. 4 is a section taken substantially on the line 4—4 of Fig. 3;

Fig. 5 is a front view of the fuse block itself, drawn to a larger scale than in Figs. 1 and 3;

Fig. 6 is an end elevation of the fuse block as viewed in the direction of the arrow 6 in Fig. 5;

Fig. 7 is a rear view of the fuse block;

Figs. 8 and 9 are longitudinal sections through the fuse block taken substantially on the lines 8—8 and 9—9, respectively, of Fig. 5;

Fig. 10 is a transverse section through the fuse block taken on the line 10—10 of Fig. 5;

Fig. 11 is another transverse section through the fuse block taken on the line 11—11 of Fig. 7;

Figs. 12, 13 and 14 are rear, side and end views, respectively, of a main switch used in the instant fuse block; and

Figs. 15, 16 and 17 are rear, end and side views, respectively, of an auxiliary switch used in the instant fuse block.

Referring to the drawings, and more especially to Figs. 1 to 4 thereof, the reference numeral 20 designates a fuse block or receptacle which, in the present instance, is of the pull-out switch type and enclosed in a panel box or metal enclosure 22. The panel box 22, which is open at the front thereof, is normally closed thereto by a trim or cover plate 28 which is removably mounted on the panel box 22 in any suitable manner, as by screws 30 which are threadedly received by lugs 32, respectively, in the interior of the panel box. The fuse block or receptacle 20 is mounted on the rear wall 36 of the panel box 22 in a manner to be described, and the trim plate 28 is provided with an inwardly offset opening 38 in which to expose the front face 40 of the mounted fuse block 20 in the manner shown in Figs. 1 and 5. The opening 38 in the trim plate 28 is normally closed by a hinged door 42 on the latter. A latch 46, preferably of spring type, on the door 42 serves for releasably locking the latter in its closed position to a lug 48 on the trim member 28. The rear wall 36 of

55

the panel box 22 is, preferably in embossed portions 59 thereof, provided with apertures 52 for the reception of screws or other suitable fasteners by means of which to mount the panel box on any suitable upright support. The panel box 22 may in any of its walls be also provided with the usual knock-outs (not shown) through which to pass the wiring with which the fuse block is connected.

Referring now to Figs. 5 to 11, inclusive, there is shown the fuse block 20 which may advantageously be molded in one piece from any suitable insulating material, such as "Bakelite," for instance. The block 20 is in the rear and at the top thereof provided with opposite ribs 21 (Figs. 7 and 8) by means of which the block 20 is suspended from hooks 23 on the rear wall 36 of the panel box 22 (Fig. 4). The block 20 is further secured to the rear wall 36 of the panel box 22 by screws 25 (Figs. 3 and 4). Provided in the fuse block 20 on opposite sides of its longitudinal center line are receptacles 60 and 62, respectively, for the reception of main switches 64 and 66, respectively, which, in the present instance, are of the pull-out type (Figs. 3 and 12). Provided in the receptacle 60 is a "live" contact 78 which may be of the clip-type shown in Fig. 10. Contact 78 is, by means of screws 80, secured to the bottom 76 of the receptacle 60 and connected with a terminal 78 (Figs. 5 and 10). The terminal 78, being a lead-in terminal for one of the live wires of a three-wire supply system, extends through an opening 82 in the adjacent end wall 84 of the block 20 (Fig. 6) and carries conventional clamp-on provisions 86 for the line wire.

Provided in the other receptacle 62 is another "live" contact 90 which may be of the same clip-type as the contact 78 in the receptacle 60, and is secured to the bottom 91 of the receptacle 62 and connected with a terminal 92 by screws 94 (Fig. 10). The terminal 92, which is a lead-in terminal for the other live wire of the three-wire supply system, extends through an opening 96 in the adjacent end wall 84 of the fuse block 20 and carries wire clamp-on provisions 98.

Further provided in the receptacle 60 is another clip-type contact 100 which is a companion to the adjacent contact 78 and connected with the latter by the main switch 64 when the same is in its circuit-closing position in the receptacle 60 (Figs. 1 and 3). The contact 100 is secured to the bottom 76 of the receptacle 60 and connected with a bus bar 102 by screws 104 (Figs. 5 and 9).

Further provided in the receptacle 62 is another clip-type contact 110 which is a companion to the adjacent contact 90 and will be connected with the latter by the main switch 66 when the same is in its circuit-closing position in the receptacle 62 (Figs. 1 and 3). The contact 110 is secured to the bottom of the receptacle 62 and connected with a bus bar 112 by screws 114 (Fig. 5).

Provided on one side of the block 20 are a number of pairs of companion terminals 120 and 122, respectively, for connection with a like number of branch circuits, respectively. The terminals 120 are live-wire terminals, being connected with the contact 100 in the receptacle 60 in a manner hereinafter described, while the terminals 122 are neutral-wire terminals being connected in a manner to be described with a lead-in terminal 124 for the neutral wire of the three-wire supply system. More particularly,

the terminals 120 and 122 are so closely coordinated (Figs. 4 and 5) that the terminal pairs 120a, 122a to 120e, 122e are readily recognized as the correct connections for the respective branch circuits.

The fuse block 20 is provided on the other side thereof with pairs of terminals 124 and 126, respectively, preferably for connection with the same number of branch circuits as on the opposite side of the fuse block. The terminals 124 and 126 are live and neutral-wire terminals, respectively, which in a manner described hereinafter are connected with the contact 110 and with the neutral-wire lead-in terminal 124, respectively. As in the case of the terminals 120 and 122, the terminals 124 and 126 are arranged in closely coordinated pairs 124a, 126a to 124e, 126e (Fig. 5) which are readily recognized as the correct connections for the respective branch circuits.

The connection between the contact 110 and each of the live-wire terminals 124 has an interposed fuse F which may be of the screw type shown in Fig. 5. To this end, the fuse block 20 is in its front face and along one side provided with openings 130 for the reception of metallic sockets 132 (Fig. 8) which are associated with the adjacent terminal pairs 124a, 126a to 124e, 126e in the manner shown in Fig. 5. The sockets 132 serve for the reception of the fuses F. The live-wire terminals 124 are, in the present instance, formed by lateral extensions 134 on the bottoms of the sockets 132, respectively. Each terminal 124 is provided with a screw 136 for the connection therewith of the live wire of the respective branch circuit. While each socket 132 constitutes one terminal for the inserted fuse F, the other terminal therefor is formed by the head of a conductive screw 138 (Fig. 8) which passes through an insulating washer 140 in the bottom of the socket and through a wall 144 in the block 20, and is threadedly received by a bus bar 146 which, as shown in Fig. 7, is connected at 148 with a conductive bar 150 that is, in turn, connected at 152 with the bus bar 112. The bus bar 150 and the sockets 132 are held in place in the block 20 by the screws 138 (Fig. 8). The neutral-wire terminals 126 are provided with screws which are received in a bus bar 160 that extends over longitudinally spaced side lugs 162 on the block 20 and is secured to the endmost of these lugs 162 by screws 164 (Fig. 7). The bus bar 160 is through a transverse bar 166 connected with the lead-in terminal 124 for the neutral line wire (Fig. 7). The transverse bar 166 extends beneath the receptacles 60 and 62 and is thus effectively insulated from the hot terminals 78 and 92 in these receptacles by the bottom 76 of the latter (Fig. 10).

The block 20 is in its front face 40 provided with further openings 130' (Figs. 5 and 10) which, in the present instance, are equal in number to the openings 130, and adapted for the reception of sockets 132' for screw-type fuses F' for further branch circuits. The bottoms of the sockets 132' have lateral extensions 134' (Fig. 10) which form the live-wire terminals 120, respectively. While each of the sockets 132' constitutes a terminal for an inserted fuse F', the other terminal therefor is formed by the head of a conductive screw 138' (Fig. 10) which passes through an insulated washer 140' in the bottom of the socket and through a block wall 142', and is threadedly received by a bus bar 146' which, as shown in Fig. 7, is connected at

170 with a conductive strip 172 that is, in turn, connected at 174 with the bus bar 102. The neutral-wire terminals 122 are provided with screws which are threadedly received by a bus bar 160' that extends over spaced side lugs 162' on the block 20 and is secured to the endmost of these lugs by screws 164' (Fig. 7). The bus bar 160' is connected at 165 with the transverse bar 166 which, as previously described, is connected with the lead-in terminal 124 for the neutral line wire.

Referring now to Figs. 12 to 14, the main switches 64 and 66, which in their circuit-closing position in the block 20 (Figs. 1, 3 and 4) are adapted to connect the contacts 70 and 100 and the contacts 90 and 110, respectively, are in the present instance identical. Thus, each main switch comprises a preferably molded insulating frame 180 having a front cover plate 182 and a depending circumferential skirt 184 which fits into either of the receptacles 60 or 62 in the block 20. Suitably mounted, as by screws 192 and 194, on the inside of the top cover plate 182 of each switch are contacts 196 and 198. Connection between the contacts 196 and 198 on each switch is made by a cartridge-type fuse 204, the contact ends 206 and 208 of which are releasably held in conductive clips 210 and 212, respectively, which are connected at 214 and 216 with the contacts 196 and 198, respectively, in each switch. The switches 64 and 66 are, in the present instance, joined by a plate 210 across their front cover plates 182 so that these switches form a unit for simultaneously opening or closing all branch circuits with which the instant block 20 is connected. The connecting plate 210 has preferably pivotally mounted thereon a handle 188 for the simultaneous manipulation of both switches 64 and 66. Instead of joining the separate switches 64 and 66 by a connecting plate 210, the frames 180 of these breakers may be molded as a single piece. The contacts 196 and 198 of the switches 64 and 66 will, on insertion of the latter in circuit-closing position in the receptacles 60 and 62, respectively, enter between and engage the contacts 70, 100 in receptacle 60 and the contacts 90, 110 in receptacle 62, respectively, and thereby close all branch circuits. To open these branch circuits, the switches 64 and 66 are withdrawn from the receptacles 60 and 62 and may in inverted position be inserted in these receptacles while the branch circuits remain open. The front face 40 of the block 20 preferably bears adjacent the receptacles 60 and 62 the legends "on" and "off", of which the legend "on" is exposed and readily discernible in a side notch 220 in the top cover plate 182 of the breaker 66 when both switches are in circuit-closing position in the block 20 (Figs. 1 and 3). Conversely, if the switches 64 and 66 are inserted in the receptacles 62 and 60, respectively, in circuit-opening position therein, the notch 220 in the switch 66 will expose for ready discernibility the legend "off" on the block 20. Thus, an observer may at a glance determine whether the inserted switches 64 and 66 are in circuit-closing position or in circuit-opening position. In order releasably to hold the switches 64 and 66 in their circuit-opening position in the block 20, there is provided in one of the receptacles therein, in the present instance the receptacle 60, a spring clip 226 (see also Fig. 10) which is insulatingly mounted and adapted to clamp the contact 198' (Fig. 12) in

the circuit-opening position of the switches in the block.

To protect a person, on removal of the switches 64 and 66 from the block 20 in the panel box 22, from possible contact with the only live conductors in the block, these being the live-wire terminals 78 and 92 and the live contacts 70 and 90 (Fig. 5), these live conductors 70, 78, 90 and 92 are preferably shielded by insulating covers 230 of which one is provided for each receptacle 60 and 62, although only one cover 230 is shown in the drawings. For mounting the covers 230, there are provided in each of the receptacles 60 and 62 raised lugs 232 and 234 on which may rest a cover 230 with one end 235 thereof projecting underneath the top edge 236 of the opening 96 in the end wall 84 of the block 20 (Fig. 6), while the other end of the cover may be secured, as by a screw 238, to the lug 232. Each cover 230 has a raised rib 242 (Figs. 5 and 10) which, together with the adjacent wall of the receptacle in which the cover is located, forms a guard through which the correct switch contact, but not the finger of a human hand, may move into engagement with the shielded live contact in the receptacle. Since both covers 230 are preferably alike for economy's sake in their manufacture, each cover 230 is provided with another raised rib 250 to provide a shielded passage to the switch-holding clip 226 in the receptacle 60.

In order to permit the connection with the instant block 20 of more branch circuits than is afforded by the terminals 120, 122, 124 and 126, there are provided on the associated live and neutral bus bars 146 and 160 further terminals 256 and 258, respectively (Figs. 5 and 6). Likewise, the associated live and neutral bus bars 146' and 160' at the other side of the block 20 are preferably provided with further terminals 260 and 262, respectively. Thus, in the present example, the block 20 described so far has provisions for connecting therewith twelve branch circuits, six on each side of the block. These branch circuits, being connected with neutral wire of the line, as described, carry current of approximately one-half the voltage of that across the live wires of the supply line, as will be readily understood.

The instant block 20 has also provisions for connecting therewith a branch circuit or circuits requiring the full voltage across the live wires of the three-wire supply system. To this end, the contacts 100 and 110 in the block receptacles 60 and 62, respectively, are connected with terminals 270 and 272, respectively, on one side of the block 20, by way of a fused switch 274 (Figs. 1, 3 and 15 to 17). The switch 274, which is of the pull-out type, is in its circuit-closing position received in a receptacle 276 provided in the block 20. The bottom of the receptacle 276 is provided with a plurality of slots 278, in the present instance 8, in four of which are exposed fixed contacts 280, 282, 284 and 286. The contact 280 is formed by a slotted portion of a metallic strip 290 (Figs. 7 and 11) which is mounted in place by having one end thereof inserted in a slotted lug 292 on the bottom wall 277 of the receptacle 276 (Fig. 11), and having its other end connected at 294 with a conductive strip 296 which is, in turn, connected with the bus bar 102 as at 174 (Fig. 7). Contact 282 is formed by a slotted portion of a metallic strip 300 (Fig. 7) which is mounted in place by having one end received in a slotted lug 302 on the bottom 277 of the receptacle 276, and by having its other end connected at 304 with

a conductive strip 306 which is, in turn, connected at 152 with the bus bar 112. Thus, the contacts 280 and 282, being connected with the contacts 100 and 110 in the receptacles 60 and 62, respectively, as described, are live contacts when the main switches 64, 66 are in their circuit-closing position in the block 20. The contacts 284 and 286, which are companions to the contacts 280 and 282, respectively, are formed by slotted portions of metallic strips 310 and 312, respectively, which are mounted in place by having their inner ends 311 inserted in slotted lugs 314 and 316, respectively, on the bottom wall 277 of the receptacle 276 (Figs. 7 and 11), and by being secured by screws 318 to one of the adjacent side lugs 162 on the block 20. The outer ends of the strips 310 and 312 may conveniently be formed into the terminals 270 and 272, respectively, in the manner best shown in Fig. 11.

The companion contacts 280, 284 and 282, 286 are, as already mentioned, bridged by the fused switch 274 in its circuit-closing position in the receptacle 276 (Figs. 1 and 3). To this end, the switch 274, which may have a molded frame 330 (Figs. 15 to 17), carries clip-type companion contacts 332, 334 and 336, 338 of which the contacts of both pairs are formed to provide receptacles 340 and 342 for the cylindrical contacts T of cartridge-type fuses F1 and F2, respectively. The contacts 332, 334, 336 and 338 will, on insertion of the switch 274 into the receptacle 276 in circuit-closing position therein, engage the fixed contacts 284, 280, 286 and 282, respectively, in the receptacle 276 and close the branch circuit leading from the terminals 270 and 272. To open this branch circuit, it is merely necessary to withdraw the switch 274 from the receptacle 276, unless the same circuit is already opened by the main switches 64, 66. The switch 274 may in inverted disposition be inserted in the receptacle 276 for safe-keeping therein while the associated branch circuit is open, in which case the contacts 332 to 338 will enter and be yieldingly held in the empty slots 278 in the bottom of the receptacle 276, as will be readily understood. In order to indicate to an observer whether the switch 274 is in its circuit-closing or circuit-opening position in the receptacle 276, the front face 40 of the block 20 preferably bears on the opposite sides of the receptacle 276 the legends "on" and "off," respectively. When the switch 274 is in its circuit-closing position in the receptacle 276, a side notch 360 in the switch front cover 362 exposes the legend "on" adjacent the receptacle 276, while a marginal extension 364 on the opposite side of the switch front cover 362 covers the legend "off" on the opposite side of the receptacle 276. Conversely, when the switch 274 is inserted in the receptacle 276 in its circuit-opening position therein, a side notch 366 in the switch front cover 362 will expose the legend "off," while the front cover extension 364 will cover the legend "on." The switch 274 is for its manipulation provided with a pivoted handle 375. For ready guidance of the contacts 332 to 338 on the switch 274 into the aligned slots in the bottom of the receptacle 276 into either the circuit-opening or circuit-closing position of the switch, the latter is provided with opposite guide ribs 368 and 370 which are slidably received in opposite guide grooves 372 and 374 in the block 20.

The block 20 may, for its connection with another full-voltage branch circuit, be provided with further live-wire terminals 376 and 378 (Fig. 5) which are connected with the contacts 100

and 110 in the receptacles 60 and 62, respectively, by way of a pull-out type switch 380 (Figs. 1 and 2) and in a receptacle 382 in the block 20 (Fig. 5). The switch 380 may, with one exception to be described, be exactly like the described switch 274, and its fuse-connected contact pairs will, in the circuit-closing position of the switch 380 in the receptacle 382, connect the contacts 384 and 386 and the contacts 388 and 390, respectively, in said receptacle. As shown in Figs. 7 and 11, the contacts 384 and 388 are formed by slotted portions of conductive strips 392 and 394, respectively, which are similar to and mounted like the strips 310 and 312 on the opposite side of the block 20. Also the outer ends of the strips 392 and 394 are formed into the terminals 376 and 378, respectively (Fig. 11). The other fixed contacts 386 and 390 in the receptacle 382 are provided by slotted portions of the previously described conductive strips 290 and 300, respectively, (Fig. 7). Thus, on inserting the switch 380 in the receptacle 382 into its circuit-closing position therein, in which the front cover 396 of the switch exposes the legend "on" adjacent the receptacle 382 (Figs. 1 and 3) the branch circuit leading from the terminals 376 and 378 is connected with the live wires of the three-wire supply system when the main switches 64, 66 are in their circuit-closing position in the block 20, as will be readily understood. The switch 380 is, for the correct guidance of its contacts into the aligned slots in the bottom of the receptacle 382 provided with opposite guide ribs (not shown) which are slidably received in opposite guide grooves 400 and 402 in the opposite sides of the receptacle. The guide ribs on the switch 380 are preferably differently dimensioned than those on switch 274 so that these breakers may not interchangeably be used in the receptacles 276 and 382, but only in the ones with which they are positively identified by suitable legends on their respective front covers, describing the type of service for which the respective branch circuits are intended, such as for a cooking range and for a water heater, for instance.

The neutral bus bars 160 and 160' on the opposite sides, respectively, of the block 20 are provided with further terminals 410 and 412, respectively (Fig. 5). Thus, either one of the branch circuits leading from the terminals 270 and 272 and from the terminals 376 and 378, respectively, may, if desired, be supplied with current of approximately one-half the voltage of that across the live wires of the three-wire supply system, by simply connecting either side of the circuit with the adjacent neutral-wire terminal 410 or 412, as will be readily understood.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent is:

1. A distribution unit for a three wire system, comprising an insulation body provided with two laterally spaced rows of receptacles for current-interrupting devices, each of said receptacles having a wire terminal for a branch circuit, said terminals of the receptacles of each row being mounted on said body and disposed adjacent the companion receptacles, respectively, three laterally spaced bus bars mounted on said body in position between and parallel to said rows of

receptacles, one of said bus bars being arranged for electrical connection to the receptacles of one of said rows and another of said bus bars being arranged for electrical connection to the receptacles of the other of said rows, and two further rows of branch circuit terminals electrically connected to the third bus bar and mounted on said body, the terminals of said last mentioned rows being positioned adjacent the terminals of the receptacles of said two rows, respectively, and insulated therefrom by said body, each of said terminals which are connected to said third bus bar being arranged on said body in paired branch-circuit relation with a terminal of the adjacent receptacle said body having at least a pair of additional branch circuit terminals aligned with each of said two further rows, respectively, one terminal of each of said pairs being arranged for electrical connection to said one bus bar and the other terminal of each of said pairs being arranged for electrical connection to said other bus bar.

2. A distribution unit as defined in claim 1, further comprising a first additional terminal in each of said two further rows and connected to said third bus bar, and a second additional terminal aligned with each row of receptacles, respectively, and connected to the bus bar to which its receptacle row is connected, said additional terminals being in paired branch-circuit relation, respectively. 30

3. A distribution unit as defined by claim 1, further comprising an additional terminal adjacent each pair of said additional branch circuit terminals, said additional terminal being arranged for electrical connection to said third bus bar and being adapted for alternative electrical connection with a branch circuit which is also electrically connected with one of the terminals of the adjacent pair of said additional branch circuit terminals. 35 40

4. A distribution unit for a three wire system, comprising an insulation body provided with two laterally spaced rows of receptacles for current-interrupting devices, each of said receptacles having a wire terminal for a branch circuit, said terminals of the receptacles of each row being mounted on said body and disposed adjacent the companion receptacles, respectively, three laterally spaced bus bars mounted on said body in position between and parallel to said rows of receptacles, one of said bus bars being arranged for electrical connection to the receptacles of one of said rows and another of said bus bars being arranged for electrical connection to the receptacles of the other of said rows, and two further rows of branch circuit terminals electrically connected to the third bus bar and mounted on said body, the terminals of said last mentioned rows being positioned adjacent the terminals of the receptacles of said two rows, respectively, and insulated therefrom by said body, each of said terminals which are connected to said third bus bar being arranged on said body in paired branch-circuit relation with a terminal of the adjacent receptacle, said body having at least a pair of additional branch circuit terminals aligned with each of said two further rows, respectively, one terminal of each of said pairs being arranged for electrical connection to said one bus bar and the other terminal of each of said pairs being arranged for electrical connection to said other bus bar, each of said two further rows including an additional branch circuit terminal adjacent each of said pairs of additional branch

circuit terminals, respectively, for optional use with the latter.

5. A distribution unit for a three wire system, comprising an insulation body provided with two laterally spaced rows of receptacles for current-interrupting devices, each of said receptacles having a wire terminal for a branch circuit, said terminals of the receptacles of each row being mounted on said body and disposed adjacent the 10 companion receptacles, respectively, three laterally spaced bus bars mounted on said body in position between and parallel to said rows of receptacles, one of said bus bars being arranged for electrical connection to the receptacles of one 15 of said rows and another of said bus bars being arranged for electrical connection to the receptacles of the other of said rows, and two further rows of branch circuit terminals electrically connected to the third bus bar and mounted on said 20 body, the terminals of said last mentioned rows being positioned adjacent the terminals of the receptacles of said two rows, respectively, and insulated therefrom by said body, each of said terminals which are connected to said third bus 25 bar being arranged on said body in paired branch-circuit relation with a terminal of the adjacent receptacle, each of said one and said other bus bars being provided with an additional branch terminal at an end thereof, and said third 30 bus bar having an additional branch terminal in alignment with each of said two further rows, respectively, each of said latter additional terminals being disposed adjacent one of said first mentioned additional terminals, respectively.

35 6. A distribution unit for a three wire system, comprising an insulation body provided with two laterally spaced rows of receptacles for current-interrupting devices, each of said receptacles having a wire terminal for a branch circuit, said
40 terminals of the receptacles of each row being mounted on said body and disposed adjacent the companion receptacles, respectively, three laterally spaced bus bars mounted on said body in position between and parallel to said rows of receptacles, one of said bus bars being arranged
45 for electrical connection to the receptacles of one of said rows and another of said bus bars being arranged for electrical connection to the receptacles of the other of said rows, and two further rows of branch circuit terminals electrically connected to the third bus bar and mounted on said body, the terminals of said last mentioned rows being positioned adjacent the terminals of the receptacles of said two rows, respectively, and insulated therefrom by said body, each of said
50 terminals which are connected to said third bus bar being arranged on said body in paired branch-circuit relation with a terminal of the adjacent receptacle, an additional branch circuit terminal at each end of said two further rows of branch circuit terminals, a branch circuit terminal aligned with each row of receptacles, respectively, one of said last mentioned branch terminals being arranged for electrical connection to said one bus bar and the other of said
55 last mentioned branch terminals being arranged for electrical connection to said other bus bar, each of said last mentioned branch circuit terminals being disposed on said body adjacent one
60 of said additional branch circuit terminals in each of said two further rows, and an additional pair of branch circuit terminals on said body arranged for electrical connection to said one and said other bus bars, respectively, each of said
65 additional pairs being aligned with one of said
70

11

further rows and being disposed adjacent the other of said additional branch circuit terminals in each of said two further rows.

7. A distribution unit for a three wire system, comprising a body of insulating material provided with spaced integral portions extending from opposite marginal edges thereof and below the front surface thereof, two laterally spaced rows of receptacles for current-interrupting devices defined in said front surface between said spaced portions and extending longitudinally of said marginal edges, each of said receptacles having a wire terminal for a branch circuit, said terminals of the receptacles of each row being mounted on said body and extending laterally of said marginal edges, respectively, and forwardly of said integral portions, respectively, three laterally spaced bus bars mounted on said body in position between and parallel to said rows of receptacles, two of said bus bars each having a branch underlying a row of said receptacles, respectively, and electrically connected thereto, and the third bus bar having two branches each of which is carried by the spaced portions along one of said marginal edges, and a further row of branch circuit terminals provided on each of said two branches in substantial longitudinal alignment with the adjacent terminals of said receptacles, respectively, laterally adjacent switch receptacles integral with said body and disposed between said two laterally spaced rows of receptacles, said switch receptacles being provided with dead front pull-out switches which complete the circuit between said two bus bars and said branches thereof, respectively, each of said two bus bars having an additional branch provided with a pair of spaced branch terminals each of which is aligned with one of said further rows of branch circuit terminals.

8. A distribution unit for a three wire system, comprising a body of insulating material provided with spaced integral portions extending from opposite marginal edges thereof and below the front surface thereof, two laterally spaced rows of receptacles for current-interrupting devices defined in said front surface between said spaced portions and extending longitudinally of said marginal edges, each of said receptacles having a wire terminal for a branch circuit, said terminals of the receptacles of each row being mounted on said body and extending laterally of said marginal edges, respectively, and forwardly of said integral portions, respectively, three laterally spaced bus bars mounted on said body in position

12

between and parallel to said rows of receptacles, two of said bus bars each having a branch underlying a row of said receptacles, respectively, and electrically connected thereto, and the third bus bar having two branches each of which is carried by the spaced portions along one of said marginal edges, and a further row of branch circuit terminals provided on each of said two branches in substantial longitudinal alignment with the adjacent terminals of said receptacles, respectively, laterally adjacent switch receptacles integral with said body and disposed between said two laterally spaced rows of receptacles, said switch receptacles being provided with dead front pull-out switches which complete the circuit between said two bus bars and said branches thereof, respectively, each of said two bus bars having an additional branch provided with a pair of spaced branch terminals each of which is aligned with one of said further rows of branch circuit terminals.

9. A distribution unit, as defined in claim 6, further characterized in that each of said two further rows includes an additional branch terminal adjacent each of said pairs of additional branch circuit terminals, respectively, for optional use with the latter.

10. A distribution unit, as defined in claim 8, further characterized in the provision of additional laterally adjacent switch receptacles integral with said body, said additional switch receptacles being provided with dead front pull-out switches which complete the circuit between said two bus bars and said additional branches, respectively, thereof.
